ALBERT GUNDLING, OF JERSEY CITY, NEW JERSEY.

ACROBATIC FIGURE TOY.

1,272,946.

Specification of Letters Patent.

Patented July 16, 1918.

Application filed April 29, 1918. Serial No. 231,396.

To all whom it may concern:

Be it known that I, ALBERT GUNDLING, a citizen of the United States, and resident of Jersey City, in the county of Hudson and State of New Jersey, have invented a new and useful Acrobatic Figure Toy, of which the following is a specification.

The object of this invention is to provide a novel acrobatic figure toy of entertaining character and simple construction. The toy consists essentially of a sloping ladder and a figure having automatic catches at its ends, whereby the figure will swing from rung to rung along the length of the ladder.

A further object is to provide a knockdown ladder frame stand for such a toy, which shall be of inexpensive wire rod construction and which, when erected, shall be rigid and capable of being lifted and moved about as a unit. Other objects and features of the invention will become apparent as the specification proceeds.

In the drawings:

Figure 1 is a side elevation of the toy in use, showing different positions of the figure in full and in broken lines;

Fig. 2 is a plan view of the ladder frame collapsed, intermediate portions of the spreader rods being broken away for economy of space;

Fig. 3 is a front end elevation on a smaller scale of the ladder frame erected;

Fig. 4 is a perspective view of the front board;

Fig. 5 is an enlarged side elevation of the figure;

Fig. 6 is a rear view thereof;

Fig. 7 is a side view of one of the catches shown in the act of engaging with one of the rungs; and

Figs. 8 to 10 are enlarged perspective views of the parts of one of the catches.

The preferred form of the knockdown ladder frame and stand will first be described. It will be understood, however, that I do not limit myself to the precise construction.

A ladder 1 is formed of metal side rods 2 and cross-rods or rungs 3 suitably united therewith. The forward ends of the side rods 2 are bent into upward projecting eyes 4, and their opposite ends are formed into upward projecting hooks or incomplete eyes 5, the eyes not being completed at this end 55 because it is not necessary to do so. The

two rear legs 6 are preferably united into one member by a top cross-portion 7. Laterally bent portions 8 join with the legs and pass outward through the hooks 5, thence curving around behind the hooks to join 60 with the cross-portion 7. This cross-portion, by bearing upon the side rods 2 behind the hooks 5, braces the legs 6 against spreading rearward from the operative position seen in Fig. 1. In the other direction, 65 however, the interlinked connection permits the rear leg member to swing inward, so as to lie flat with the ladder member, as represented in Fig. 2.

The front legs 9 are shorter than the rear legs, so that when the frame is erected the latter is supported in a sloping position. The interlinked bracing connection between the forward legs and the ladder member resembles that between the ladder and the rear legs, but at the front there is no connecting cross-portion between the legs for a reason which will appear. The front legs are also made of wire rods and are formed at their upper ends with hooks 10, which are bent 70 laterally outward and face inward with respect to the longitudinal central plane. The portions 8a of these hooks, corresponding to portions 8 of the rear leg member, pass outward through the eyes 4 from the inner 75 sides, while their portions 7a, corresponding in bracing effect to the cross-portion 7, bear upon the side rods 2 of the ladder in rear of the eyes. In this way the legs 9 are braced against spreading forward from the 80 outward position of Fig. 3, but are free to hinge in the opposite direction and may be unthreaded entirely from the eyes.

The front and rear legs are spread forwardly and rearwardly, respectively, by 85 longitudinal base rods 11, the length of which is such as to cause the bracing portions of the leg and ladder members to contact and to place the whole structure under tension, in order that when erected it may 90 constitute a substantially rigid portable unit. The rear ends of the spreader rods 11 are separably interlinked with the lower ends of the legs 6 by means of hooks and eyes 12 and 13. In this instance the forward ends of the base rods are not directly connected with the lower ends of the legs 9, but both of these pairs of rods are engaged with a front board 14 having a pair of holes 15, 16 in each side. The lower ends 110

17 of the front legs are bent horizontally inward to enter the holes 15 and in like manner the ends 18 of the spreader rods are bent inward to engage the holes 16.

5 The figure 19 may have any semblance desired. It is of suitable weight and construction and of a length approximating the distance between the rungs 3 of the ladder. At its opposite ends are catches 20 which 10 cause the figure alternately to catch and release the rungs as it swings from rung to rung from the higher to the lower end of the ladder. These catches may be rigidly held in the bifurcated ends 21 of a continuous frame 22 extending through the interior of the figure. In the best embodiment, each catch comprises a pivoted yielding latch 23 and a slidable stop 24 located opposite each other at front and back, with a channel 25 15 between them for the reception of the rungs. The said latch and stop are mounted in a box-like frame 26. The wall 27 of this frame I shall term for convenience the back wall. In the upper catch this back wall is 20 toward the front of the figure, and in the lower catch toward the rear, owing to the fact that the catches with their channels 25 are reversed. The stop 24 of each catch is formed in a simple manner by bending a 25 strip of metal into a flat loop embracing the said back wall 27, this flattened loop being longer than the wall so that it may slide in and out thereon lengthwise of the figure. The rear or inner portion of each stop is 30 slotted at 28, to accommodate the spring 29 of the latch 23. The said latch is mounted upon a pivot 30 within the frame 26 and adjacent its front wall 31. The spring 29 is connected with a tail 32 on the latch, and the 35 wall 31 constitutes an abutment which supports the latch in normal position against the pull of said spring while permitting it to yield toward the stop 24. The side walls of the frame 22 have their edges 33 cut on a 40 curve or slant to form one side of the channel 25. The opposite side of this channel is constituted by the outer portion 34 of the latch 23, which is bent toward the stop 24 and which is bent or curved so as to correspond generally to the conformation of the 45 inner edges 33 of the channel.

A stout spike or peg 35 projects from the seat of the figure, for the purpose which will now appear.

50 In operation the catch at one end of the figure, preferably the upper end, is engaged with the first rung of the ladder, the figure being held outward in the substantially horizontal position shown in Fig. 1. In this condition the bottom of the channel 25 rests upon the rung, the said bottom being formed by the latch 23 supported by the wall 31 of the frame 22. The figure, now being released, swings downward and forward until its lower catch engages the next

rung of the ladder. As the figure swings down, gravity causes the sliding stop 24 of the upper catch to slip in (assuming that it was previously projecting) and at the same time gravity and centrifugal force cause the stop of the lower catch to slip out. When the said lower catch reaches the next rung of the ladder, its latch 23 strikes the said rung and springs past and over it. Immediately thereafter the projected stop 24 of this catch strikes the under side of this rung and prevents further upward swinging of this end of the figure. The catch which was engaged with the first rung now slips off this rung, and the opposite catch becomes fully 75 engaged with the second rung. In this transferring movement the curved or inclined side 33 of the channel of the disengaging catch and the curved or inclined lip of the latch 23 of the engaging stop cause the figure 80 to slip for a short distance endwise. These operations are repeated as the figure proceeds along the ladder. At the last rung the figure swings out into the air and then drops in a sitting posture, its weight causing the 85 spike 35 to penetrate the board 14, so that the figure is sustained in this position.

While the preferred embodiment of the invention has been described and illustrated in detail, it will be understood that I do not necessarily confine myself as to matters of form, proportion and detail, and that numerous changes may be made without departing from the invention.

What I claim as new is:

1. A toy comprising a sloping ladder and a figure having catches at opposite ends and adapted to swing automatically from one rung to another along the ladder. 100
2. A toy comprising a sloping ladder, a figure, and means at opposite ends of the figure for automatically catching and releasing the rungs of the ladder, whereby the figure will swing from rung to rung and drop in a sitting position at the end. 105
3. A toy comprising a sloping ladder, a figure, and means at opposite ends of the figure for automatically catching and releasing the rungs of the ladder, whereby the figure will swing from rung to rung and drop in a sitting position at the end, the figure having a prong in its seat to stick in a base. 110
4. A toy comprising knockdown members adapted to be erected to form a frame supporting a sloping ladder, and a figure having means at the ends for alternately catching and releasing the rungs of the ladder. 115
5. A toy comprising a ladder adapted to be supported in a sloping position and in combination therewith a figure having automatic catches at its ends whereby it will swing from rung to rung, each of said catches comprising a yielding latch and a slidable stop. 120
6. A toy comprising a ladder adapted to 125

be supported in a sloping position and in combination therewith a figure having automatic catches at its ends whereby it will swing from rung to rung, each of said 5 catches including a sliding stop.

7. A toy comprising a ladder adapted to be supported in a sloping position and in combination therewith a figure having automatic catches at its ends whereby it will 10 swing from rung to rung, said catches comprising yielding latches and sliding stops and presenting reversed channels which receive the rungs, the sides or edges of said channels being formed to slide on the rungs 15 at the moment of transfer from one rung to the next.

8. A toy comprising a ladder adapted to be supported in a sloping position and in combination therewith a figure having automatic 20 catches at its ends whereby it will swing from rung to rung, each of said catches including a yielding spring-urged latch.

9. A toy comprising a ladder adapted to be supported in a sloping position and in combination therewith a figure having automatic catches at its ends whereby it will swing from rung to rung, each of said 25 catches including a pivoted spring-urged latch.

10. In a toy, a knockdown ladder frame comprising a ladder member, front and rear collapsible legs, and detachable longitudinal base members.

35 11. In a toy, a knockdown ladder frame comprising a ladder member, front and rear collapsible legs, detachable longitudinal base members, and a front board with which

both the front legs and the base members are adapted to engage.

12. In a toy, a knockdown sloping ladder frame comprising a ladder member, front and rear collapsible legs, said legs and ladder member being so constructed as to interlink and brace each other, and means for 45 connecting the legs at the base comprising disconnectible stretcher rods.

13. In a toy ladder frame, a ladder member having side rods formed with eyes at one end and a leg structure comprising two 50 legs having laterally bent upper portions passed through said eyes and a transverse portion continuous with and connecting said laterally bent portions and constructed to bear upon said side rods at the top and in rear of said eyes, whereby a bracing hinged connection is formed.

14. In a toy ladder frame, a ladder member having side rods formed with eyes at one end, and a pair of legs coöoperative with 55 said eyes, said legs having hooks at their upper ends bent laterally outward and facing inward, said hooks passing through the eyes from the inner sides with their free limbs overlying said side rods in bracing 60 relation.

15. A toy ladder frame comprising a ladder member, collapsible front and rear leg members interlinking with the ladder member, basal stretcher members interlinking 70 with the rear leg members, and a front board having side openings, the lower ends of the front leg members and the forward ends of the stretcher member bent horizontally inward to enter said openings.

ALBERT GUNDLING.
